[57] CLAIM

The ornamental design for a rebar and beam highchair, as shown and described.

DESCRIPTION

FIG. 1 is a top front perspective view of the rebar and beam highchair showing our new design;

FIG. 2 is a front elevational view thereof with the rear, being a mirror image thereof;

FIG. 3 is a side elevational view thereof with the opposite side being a mirror image thereof;

FIG. 4 is a top plan view thereof; and

FIG. 5 is a bottom plan view thereof.
